UNITED STATES PATENT OFFICE.

RAY B. WEEKS, OF CLEVELAND, OHIO, ASSIGNOR, BY MESNE ASSIGNMENTS, TO THE WAYNE PUMP COMPANY, OF BALTIMORE, MARYLAND, A CORPORATION OF MARYLAND.

PINION SHAFT AND METHOD OF MAKING.

Application filed May 5, 1927. Serial No. 189,122.

The invention pertains to a dispensing apparatus, and more particularly to a novel pinion shaft to be used in a fluid dispensing pump.

5 In the usual integral pinion shaft for a device such as a dispensing pump, it is usual to machine a blank or steel shaft in a number of stages and to cut pinion teeth in a certain stage thereof, using other stages, with or 10 without bearing sleeves, as bearings. This is objectionable as it is expensive to manufacture, and as the grain of the steel runs lengthwise of the teeth, a weaker tooth is produced than if the grain thereof ran radially.

15 It is, therefore, an object of this invention to produce a pinion shaft for cooperating with the pump rack, which is of integral structure, yet is inexpensive to manufacture.

Another object is to produce a pinion shaft 20 with a bearing of larger surface without necessarily increasing the shaft diameter per se.

A further object is to manufacture an integral pinion shaft whereby the pinion may 25 be cut from an upset portion of the shaft, thereby insuring an integral and stronger structure.

A still further object is to manufacture a 30 pinion and shaft whereby the grain of the steel in the gear teeth runs radially, from the root of the teeth to the tip, thereby more effectively resisting breaking than in the case where the grain runs parallel to the axis of the shaft.

35 With these and various other objects in view, the invention may consist of certain novel features of construction and operation, as will be more fully described and particularly pointed out in the specification, drawings and claims appended hereto.

40 In the drawings which illustrate an embodiment of the device, and wherein like reference characters are used to designate like parts,—

45 Figure 1 is a sectional elevation of a fluid dispensing pump embodying the invention;

50 Figure 2 is a partial sectional elevation taken through the upper cylinder head or pinion housing and showing the rack and pinion bearings and guides;

Figure 3 is a sectional plan of the rack

and pinion, taken substantially along the plane indicated by the line 3—3 of Figure 1; and

55 Figure 4 is a view similar to Figure 3 taken along the plane indicated by the line 4—4 of Figure 1.

Figure 5 is a longitudinal elevation of a pinion blank;

60 Figure 6 is a longitudinal elevation of the pinion blank after the first upsetting step showing the enlargement of the shank or shaft portion;

65 Figure 7 is a longitudinal elevation of the pinion blank after cutting the teeth on the upset portion and machining the shanks to correct size;

70 Figure 8 is a longitudinal elevation of the pinion blank illustrated in Figure 7, after the bearing collar has been secured or shrunk on a portion of the shank.

75 Referring first of all to one application of the pinion shaft, the usual oil pump 1 provided with the inlet 2, from a supply reservoir, and the outlet 3 disposed conveniently above the drip pan 4, is provided with a pump or piston cylinder 5 which acts as a guide, and a reservoir on the up stroke of the piston 6, said piston and cylinder being provided with the usual one-way valves. The piston 6 is 80 adapted to be actuated by the usual handle 7 attached by means of the nut 7^a to the pinion shaft 14 carried in convenient bearings 12 and 13 in the upper cylinder head 8 attached to and supported by the piston cylinder reservoir 5.

85 Cooperating with the pinion and attached to the piston is a rack 10, formed on a cylindrical bar, which slides in a suitable guide 11 formed in the head adjacent the bearings 12 and 13. The pinion shaft 14 is provided with a bearing surface 19 adapted to fit in a suitable opening or bearing surface in the bearing 12, this bearing surface 19 being adjacent the pinion teeth 15 and disposed 90 at one end of the shaft. A sleeve 18 is forced on the shaft 14 and is disposed adjacent the teeth 15 on the opposite side to the bearing surface 19 and is adapted to turn in the bearing 13. The bearing 13 is provided with 95 a suitable threaded portion for taking the positioning and bearing member 16. Be-

tween the member 16 and the sleeve 18, there may be provided any packing, such as indicated at 17.

In manufacturing this pinion shaft arrangement, it has been found convenient to use a suitable rod or wire 25, upsetting a portion 26 thereof at the desired place as adjacent one end, which upsetting operation, it will be understood, slightly increases the 10 two ends 30 and 31 above their normal size which may be illustrated by the upset and final diameters 27 and 28. This necessitates a turning operation, a certain amount of metal being removed all over to reduce the 15 diameter of the shaft to the working diameter 28. The teeth 29 are cut in the upset portion 26 of the pinion shaft in the usual manner on a gear hob. The sleeve 18 is then forced on one end of the shaft and disposed adjacent 20 the teeth 15 in order to give a larger bearing surface. It is, of course, to be understood that this sleeve, which may be of slightly larger diameter than the outside 25 diameter of the teeth, may be formed integral with the pinion shaft although it has been found more convenient to use a separate sleeve. It has further been found that in forming the teeth in the above manner that the grain in the teeth is disposed in a 30 direction from the root to the tip and not in the direction of the axis or longitudinal center line of the shaft, thereby increasing the strength of the member, which may allow 35 smaller parts to be used for the same stresses to be encountered.

It is to be understood that I do not wish to be limited by the embodiment shown of the device, which is merely by way of illustration and not limitation, as various and 40 other forms of the device will, of course, be apparent to those skilled in the art, without

departing from the spirit of the invention or the scope of the claims.

I claim:

1. The method of forming a pinion shaft, 45 which includes upsetting a portion of said shaft, cutting teeth on said upset portion, and positioning a bearing adjacent said teeth, said bearing having an outside diameter at least as great as the outside diameter of the 50 teeth.

2. The method of forming a pinion shaft, which includes upsetting a portion of said shaft, cutting teeth on said upset portion, machining said shaft, and positioning a 55 bearing adjacent said teeth, said bearing having an outside diameter at least as great as the outside diameter of the teeth.

3. The method of forming a pinion shaft, which includes upsetting a portion thereof, 60 cutting teeth on said upset portion, and providing a bearing on said shaft adjacent said teeth, said bearing having an outside diameter at least as large as the outside diameter of said teeth.

4. The method of forming a pinion shaft, which includes upsetting a portion thereof, cutting teeth on said upset portion, and providing bearings on said shaft, at least one 65 of said bearings having an outside diameter 70 at least as large as the outside diameter of said teeth.

5. In a pinion arrangement the combination of a cylindrical portion having an upset portion therein, teeth formed in said upset portion and a sleeve secured to said cylindrical portion adjacent said teeth, the diameter of said sleeve being at least as great 75 as the diameter of said teeth.

Signed at Cleveland, Ohio, this twenty- 80 fifth day of April, 1927.

RAY B. WEEKS.
